US00D431068S

United States Patent [19]

Beaver et al.

[11] Patent Number: Des. 431,068

[45] Date of Patent: ** Sep. 19, 2000

[54] SPRAYER

[75] Inventors: **Larry Gene Beaver**, Lake Park, Ga.; **Mark T. MacLean-Blevins**, Westminster, Md.; **Craig Stephen Ketcham**, Somerset, Pa.

[73] Assignee: **Griffin LLC**, Valdosta, Ga.

[**] Term: 14 Years

[21] Appl. No.: 29/111,582

[22] Filed: Sep. 30, 1999

[51] LOC (7) Cl. 23-01

[52] U.S. Cl. D23/213; D23/225

[58] Field of Search D23/213, 225; 239/310, 312, 314, 316-8
